(57) **CLAIM**

The ornamental design for an assembling game plate, as shown and described.

DESCRIPTION

FIG. 1 is a front view of an assembling game plate of the present invention comprising a rotatable “head and arms part” and “body and legs part”.

FIG. 2 is a rear view thereof.

FIG. 3 is a top plan view thereof.

FIG. 4 is a bottom plan view thereof.

FIG. 5 is a right side view thereof.

FIG. 6 is a left side view thereof.

FIG. 7 is a perspective view thereof.

FIG. 8 is a sectional view taken along the line 8-8 of the FIG. 2.

FIG. 9 is a front view thereof with “head and arms part” rotated.

FIG. 10 is a front view thereof with “head and arms part” rotated; and,

FIG. 11 is a front view thereof with “head and arms part” rotated.

The alternate long and short dash lines indicate bounds of the claimed design and form no part thereof.

The features shown in broken lines are included to illustrate portions of the assembling game plate and form no part of the claimed design.
